UNITED STATES PATENT OFFICE.

UHLICH MAHLER, OF SAN FRANCISCO, CALIFORNIA.

HEEL.

1,008,841.

Specification of Letters Patent. Patented Nov. 14, 1911.

Application filed April 12, 1911. Serial No. 620,577.

To all whom it may concern:

Be it known that I, UHLICH MAHLER, citizen of Canada, residing in the city and county of San Francisco and State of California, have invented new and useful Improvements in Heels, of which the following is a specification.

This invention relates to heels, and particularly to rotary heels for shoes.

10 The object of the present invention is to provide a practical, durable, self-cleaning rotary heel for shoes, and to provide a heel of such construction and design as to employ the least number of elements possible.

15 The invention consists of the parts and the combination and construction of parts as hereinafter more fully described and claimed, having reference to the accompanying drawings, in which—

20 Figure 1 is a vertical section through the heel. Fig. 2 is an underneath plan view of the stationary member. Fig. 3 is a perspective view of the turn-table plate. Fig. 4 is a perspective view of the screw.

25 In the illustrated embodiment of my invention, 2 indicates a portion of a shoe or slipper, to the lower heel portion of which is connected a stationary heel section 3, which may be of any suitable material, such as rubber, leather, wood, fiber, etc., and which is attached to the shoe by means of screws or nails 4 insertible through perforations 5 provided for their reception in the stationary section 2.

35 The salient and important feature of the present invention is the means for attaching to and supporting against the stationary section of the heel, a turnable circular, or otherwise shaped, wearing section 6, which may 40 be of suitable proportions as regards height and diameter, and which is adapted to revolve freely so as to constantly present its wearing surface in different angular positions for the purpose of insuring a substantially uniform and even degree of wear on its lower surface.

Another important feature of the present invention is to provide a turnable heel which may be cheaply and easily manufactured, and which will be permitted to revolve with great freedom.

50 In accomplishing these purposes I provide and insert into the lower surface of the stationary section 3 of the heel a metallic or other plate 7, of suitable diameter and thick-

ness, and which may be notched, as at 8, so as to be better secured against movement on the section 3. In the present instance the plate 7 is shown as inserted in the stationary member 3 so as to form a recess or depression having beveled edges 9 formed by the material of the section 3. This plate 7 is provided with an annular raceway 10, which may be semicircular in cross section or V-shaped, or otherwise designed, and in which is adapted to run a series of antifrictional devices, as, for instance, balls 11, which are held in their raceway 10 by the turnable heel section 6.

55 The turnable heel section 6 is pivotally connected to the stationary section 3 by means of a central stud, here indicated as a screw 12, inserted from the top of the stationary member 3 and having its head 13 filling a recess 14 formed for its reception in the upper surface of the stationary heel section 3. Preferably the material of which the section 3 is formed projects beneath the head 13 of the screw and nearly contacts with the shank of the screw 12. The object 70 of providing this material beneath the head 13 of the screw 12 is so that when the heel member 6, which is provided with a wearing or face plate 15, is drawn up by the screw 12 as it engages the threads 16 formed in 75 the central portion of the wearing plate 15, the wearing plate will ride upon the balls 11 in the raceway 10, and by reason of the packing beneath the head 13 of the screw, all 80 rattle of the heel section 6 is prevented.

85 In order to provide for ample engagement with the threads of the screw 12, the bearing plate 15 is somewhat depressed at its central portion forming a collar or flange threaded, as at 16, to receive the screw, and this plate 15 may be appropriately secured in the heel 6, which may be of any suitable material, as rubber, leather, fiber, wood, etc.

90 In the present instance I have shown the wearing plate 15 as provided with integrally formed spurs 17, which may be punched upwardly from the body of the plate, and which are adapted to be driven or otherwise secured in the material of which the turnable heel section 6 is formed.

100 In operation, the stationary member 3 is placed upwardly against the bottom of the shoe 2 after the screw 12 has been inserted through the opening provided for its reception, and then the section 3 is tacked, or 105

110

otherwise secured, to the shoe. The shoe with the stationary portion attached is then turned over so that the screw 12 projects upwardly through the stationary member 3, and the balls 11 are arranged in the race-way 10, after which the turnable section 6 is threaded down over the screw 12 until it has a reasonable free running motion upon the balls 11. The screw is prevented from 10 revolving when the heel section 6 is screwed on by inserting in a slot 18 in the point of the screw a screw-driver holding the screw against rotation.

After the heel has been screwed to the 15 desired position, a tool may be inserted through the opening 19 in the center of the turnable section 6 until it bears against the edge of the threaded portion 16 of the wearing plate 15, and by giving the tool a slight 20 blow with a hammer, the threaded portion 16 will be depressed into one of the slots 20 formed in the sides of the screw 12, thus keying the turnable section 6 to the screw 12 so that the latter will revolve uniformly 25 with the heel section 6 and also be prevented from unscrewing.

This heel, as here described, will be self-cleaning during the time of its service by reason of the downwardly beveled edges 9 30 of the stationary section 3, which permit sand, dust and other material which may have worked its way between the working joint of the movable section and the stationary section to gradually sift outwardly and 35 downwardly, and this self-cleaning action may be enhanced by beveling the upper circumferential edge of the turnable heel 6.

The opening 19 in the tread member 6 may be closed by cementing or otherwise attaching a filler or plug 21 insertible in the 40 heel.

Having thus described my invention, what

I claim and desire to secure by Letters-Patent, is--

1. A rotary heel comprising a stationary 45 member, a turnable tread member, a wearing plate, carried by the tread member, anti-friction elements between the stationary member and the wearing plate, and a screw carried by the stationary member and having threaded engagement with said wearing plate and being keyed thereto so as to turn therewith.

2. A rotary heel comprising a stationary member, a turnable tread member, a wearing 55 plate carried by the tread member, anti-friction elements between the stationary member and the wearing plate, and a screw carried by the stationary member and having threaded engagement with said wearing plate and being keyed thereto so as to turn 60 therewith, said screw having an enlarged head and said stationary member having a recess to receive said head.

3. A rotary heel comprising a stationary 65 member, a turnable tread member, a wearing plate carried by the tread member, anti-friction elements between the stationary member and the wearing plate, and a screw carried by the stationary member 70 and having threaded engagement with said wearing plate and being keyed thereto so as to turn therewith, said screw having a nick in its outer end, and said tread member having an opening for the screw 75 affording access to the nick thereof.

In testimony whereof I have hereunto set my hand in the presence of two subscribing witnesses.

UHLICH MAHLER.
